UNITED STATES PATENT OFFICE.

MARTIN JELALIAN, OF CRANSTON, RHODE ISLAND.

VERTICALLY-OPERATED BUFFING DEVICE FOR METAL CASES.

1,384,259.

Specification of Letters Patent. Patented July 12, 1921.

Application filed November 9, 1920. Serial No. 422,982.

To all whom it may concern:

Be it known that I, MARTIN JELALIAN, a citizen of the United States, residing at the city of Cranston, in the county of Providence and State of Rhode Island, have invented certain new and useful Improvements in Vertically-Operated Buffing Devices for Metal Cases, of which following is a specification.

10 The object of the invention is to improve the buffing of the metal cases by providing a vertically operated buffing device for the entire surface of a case. The parts of the device are thus arranged that the same are 15 readily and safely operated and by the operation of the same an unusual amount of work may be obtained, more than the buffers can.

20 The detailed description of the invention is illustrated in the accompanying three sheets of drawings forming a part of this specification in which:

25 Figure 1 is a side perspective view of the improved device showing the inner slideable members in position as having been engaged with the buff-wheels or after buffing operation has been performed. Fig. 2 is a side view showing the inner slideable members as in engagement with the buff-wheels. Fig. 3 30 is the inner slideable member of the vertical base support member provided with means to buff the side faces of round cases. Fig. 4 is a vertical support member for the inner slideable member.

35 Fig. 5 is the inner slideable member as equipped with metal sections of hand bags as to be buffed upon the same. Fig. 6 is an enlarged top plan view of one of the vertical support members and the inner slideable 40 member, the vertical support member shown in section.

45 Fig. 7 is an enlarged sectional view of the vertical support member and the inner slideable member showing a snap-pin arrangement to limit the downward movement of the inner slideable member. Fig. 8 is a top sectional view of the vertical support member and the inner slideable member as equipped with a pair of standards to perform the buffing operation upon both sides thereof without shifting the inner slideable member. Fig. 9 is a modified form of arrangement of the parts of the device. Fig. 10 is another modification of the same.

55 Referring to the drawings, —a— designates a buffing bench provided with stand-

ards —b, b— secured upon the top of the same; each standard —b, b— has a buff-wheel —u— mounted upon shaft —6—.

Extending forwardly each of said buff-wheel —u, u— are vertical support members —h, h— having their lower ends secured to the floor and provided with pivotal connections —a', a'—, and said support members project through openings —e, e— formed 60 upon the bench —a— and having pull-spring connections —v, v— with having one of their ends secured to the hook —w, w— provided upon the support members —h, h— and the other ends secured to the hooks 70 —w', w'— provided upon the bench —a—.

Each vertical support member —h— has reduced integral sections —h', h'— projecting vertically parallel to each other and having a shaft upon which is secured pulley —p—.

Slidably mounted upon the said vertical support members —h, h— are slideable members —k, k— having case-setting blocks —q, q', q² and q³ projecting from one of said faces thereof for buffing the top faces of sections of cases, and also blocks —u⁹ and q⁵— for buffing the side faces of sections of cases which project from the other faces thereof; that is to say when the buffing operation is 85 performed on case setting blocks —q, q¹, q² and q³— the inner slideable members —k— may be readily shifted to perform the buffing operation on blocks —u⁹ and q⁵—.

In Figs. 3 and 6 is shown the inner slideable member as provided with movable form of case setting blocks on its one side thereof, for buffing the top faces, and also side faces of round shaped cases q⁶ and q⁹ by shifting the position of the slideable member —k—; 90 cases —q⁶— are mounted upon integral blocks —q'— which project from one side of the inner slideable member —k— to buff the top faces of sections of cases q⁶; and when the buffing operation is performed on the top faces, the slideable member may be readily shifted to perform the operation on the side faces of round shaped cases —q⁹, q⁹— which are mounted upon two integral collars provided at the ends of operating 100 shafts —r²— which are passing loosely through portions —j⁹— projecting outwardly from the slideable member k.

In order to keep the sections of cases in position upon the round shaped blocks or 110 collars of the operating shaft —r²— when engaging with the buff-wheels, vertically

arranged bars q^4 , q^4 are used which are loosely secured against sections of cases q^9 , q^9 and designed to limit the outward movement of the same when in engagement 5 with the buff wheels.

The inner slideable member k has blocks q on its one face. The latter is also provided with projecting blocks u^9 on its other face adapted to receive a square 10 shaped case on each side thereof in the same manner as in Fig. 6 with the exception that the shaft r^2 is omitted and the case setting blocks are square shaped and integral with the vertical flat projecting portions 15 q^9 as shown by Fig. 2. The inner slideable members are provided with case-setting blocks q^2 and q^3 on their rear faces for buffing side faces of the sections of cases, they are also provided with case-setting 20 blocks upon their front faces for buffing the side edges of the sections of the cases, in the same manner as shown by Fig. 2.

After the buffing operation has been performed upon the front faces of the inner 25 slideable members k , k they may be readily drawn off from the vertical support members h , h and replaced by shifting their position, this facing the front to the rear, in order to perform the buffing operation 30 on their rear faces.

Secured upon the top of the bench a behind the standards b , b are vertical supports l , l which carry shaft n at their upper ends. Said shaft n is 35 driven by belt b^9 running over pulley b^8 mounted upon the same and passing over pulley b^5 secured upon the upper main shaft e^4 .

The standards b , b are driven by main 40 belt e^3 provided with common form of pulleys and a shaft beneath the bench a . The main belt e^3 is passing over pulley e^2 mounted upon main shaft e' .

Each inner member k , k of vertical 45 slideable support members h , h is also provided with an integral hook r' , a pull-rope r is secured to said hook r' and passing over a pulley p extends to shaft n adapted to spin between 50 two integral collars a' , a' of said shaft n .

When shaft n operates the ropes r , r will spin over said shaft between the two integral collars a' , a' thus the inner 55 members k , k of the vertical support members will engage with the buff-wheels u , u to perform the buffing operation by a vertical slideably operated movement.

Each vertical support member h is 60 provided with an integral hook a' a movable support rod a^2 having its upper end pivotally connected to said hook and its lower end provided with an eyelet and slideably mounted within a moving support 65 port a^9 secured to the floor, a pin a^6

is secured in place to limit the movement of the movable support rod a^2 .

When it is desired to move the vertical support member h backward or forward, all that is required is to withdraw the pin a^6 from its holding position against the rod a^2 and the latter made free to be slideably moved within the moving support a^9 as desired and replace the pin a^6 . 75

Each vertical member h is also provided with a buffing grease applying arm k' which is pivotally connected at k^3 and having full-spring connection k^2 .

The forward end l' of the arm k' is 80 provided with a bar of buffing grease, as shown by Fig. 2.

In Fig. 5 is shown the inner slideable member as equipped with metal sections k^9 , k^9 for hand bags which may be buffed 85 upon the same.

A snap-pin connection is arranged upon one side of the vertical support member to limit downward movement of the inner slideable members k , k . Said snap-pin connection consists of an E shaped tubular member l^2 slideably mounted upon shafts l^1 , l^1 projecting from the upper part of the vertical support member h and having coil spring connections l^9 , l^9 and 90 also snap-pin r^9 which projects through the support member h to limit the downward movement of the inner slideable member k . 95

The inner end of the snap-pin r^9 is 100 a chisel end shape in order to permit the slideable member k to move upwardly, when operating and to limit the downward movement of the same after the buffing operation has been performed, as shown by 105 Fig. 7.

The tubular member l^2 is also provided with a projecting shaft r , the purpose of the same is to connect the entire set of snap-pin connections of the vertical support members h , h together if desired by arranging a horizontal connecting rod. 110

In Fig. 8 the device is shown as equipped with a pair of standards, h^2 and h' arranged to be driven oppositely one another to perform the buffing operation without shifting the position of the inner slideable member k . In this form of arrangement the vertical support member h is integral and projects through the bench in a horizontal and vertical position and provided with a pulley and rope connection in the same manner as shown by Figs. 1 and 2. The section of a case q^6 engaged with buff-wheel h^9 and the sections of a case q^5 and q^3 engage with the buff-wheel h^9 of 115 the opposite standard. 120

Fig. 9 is a modified form of arrangement of the device. In this modified form the support member h is arranged horizon- 130

tal, supported by vertical supports —*q*⁷, *q*⁷— which are pivotally connected upon the top of the bench —*a*— and provided with movable support rods *a*² having their upper ends 5 pivotally connected to the integral hooks provided upon the rear of said vertical supports —*q*⁷, *q*⁷— and their lower ends mounted within movable supports —*a*⁹, *a*⁹— which are secured to the bench —*a*— and projecting 10 inwardly therefrom.

In this modified form the standards are arranged in two, the purpose of which is to perform two operations, that is to say, the inner slidable member —*k*— after engaging 15 with the buff-wheel —*u*— of the standard —*b*— will engage with the buff-wheel —*u*— of another standard secured forwardly to the same to perform another operation.

In this arrangement the inner slidable member —*k*— is operated by rope —*r*— which is adapted to spin over the shaft —*f*⁴— secured upon supports —*f*⁹, *f*⁹— and provided with wheel —*f*²— having gear upon one side thereof which meshes with gear —*f*¹— mounted upon the forward end of shaft —*w*⁴— of the standard —*n*⁴— secured upon the top of the bench —*a*—.

Mounted upon said shaft —*w*⁴— is a pulley —*v*⁹— having a belt —*v*²— running over pulley —*b*⁵— secured upon shaft —*e*⁴—. Also mounted upon said shaft is a pulley —*e*²— provided with a belt —*e*³— to drive the standards —*b*— secured upon the bench —*a*—.

35 In Fig. 10 the device is shown as equipped with three buff-wheels to perform the buffing operation on one side of the inner slidable member —*k*—.

In this modified form the vertical member —*h*— is integral and projects through 40 the bench —*a*— in a horizontal vertical position and also having a full-rope connection and a horizontal shaft above the bench —*a*— in the same manner as in Figs. 1 and 2.

45 In this arrangement standards —*n*⁴, *n*⁴— are arranged so that they have shafts —*w*⁴, *w*⁴— provided with buff-wheels —*w*⁹, *w*⁹— at the forward ends thereof.

The standards —*n*⁴, *n*⁴— are movably mounted upon base support members —*w*², *w*²— secured upon bench —*v*— which is arranged closely opposite to the bench —*a*—.

Secured upon the bench —*a*— is a standard —*h*²— having a buff-wheel —*h*⁹— which 55 engaged with cases *q*⁵ and *q*³.

Each standard —*n*⁴— is operated in the manner as shown by Fig. 9, provided with a pulley —*v*⁹— having a belt —*v*²— passing over pulley —*b*⁵— mounted upon shaft 60 —*e*⁴—.

Thus having described the invention what I claim as new and desire to secure by Letters Patent is:

1. In combination with a buffing bench 65 having standards arranged upon the top

of the same, a vertical support member forwardly of each of said standards and having pivotally connected to the floor beneath said bench and projecting through the same in a slanting vertical position and having reduced sections extending vertically and supporting a horizontal shaft upon the upper ends thereof, a pull-rope extending from each of the inner slidable members of the said vertical support members and passing 70 through a pulley secured upon said shaft of the reduced sections of said vertical support members and adapted to spin between each pair of collars of a horizontal shaft arranged above said bench, a buffing-grease applying arm for each of said vertical support members and having pivotally connected to the reduced sections of the same and having a bar of buffing grease secured at its forward 75 end and provided with pull-spring connections at the rear ends thereof to apply buffing grease to the buff-wheels of said standards.

15 2. In combination with a buffing bench having standards arranged upon the top of the same, vertical support members forwardly of said standards and projecting through said bench and having inner slidable members, provided with case-setting blocks receiving sections of cases upon the same and engaging with the buff-wheels of said standards, vertically arranged supports behind said standards and having their lower ends secured upon the top of said bench and provided with an operative shaft 80 upon their upper ends extending horizontally above said bench and having integral collars arranged in pairs, pull ropes extending from said inner members of the vertical slidable support members and passing over pulleys mounted upon small shafts secured upon the top of the vertically extending reduced sections of said vertical support members, and extending from said pulleys to said shaft and adapted to spin between each pair of collars of said shaft.

85 3. In combination with a buffing bench having standards arranged upon the top of the same, vertical support members forwardly of said standards and said support members pivotally connected to the floor beneath said bench and projecting through the openings formed into the same and extending in a slanting vertical position forwardly to the buff-wheels of said standards, slidable members mounted within said vertical support members and having case-setting blocks 90 adapted to engage with the buff-wheels of said standards, a horizontally extending shaft above said bench, pull-rope connections between said inner slidable members and said shaft, and snap-pin connections upon one side of said vertical support members and each set consists of an E shaped tubular member slidably mounted upon a 95 pair of integral shafts projecting outwardly 100

105

110

115

120

125

130

from one side of the upper part of each of said vertical support members and having coil-spring connections and also a snap-pin passing through said vertical support members and adapted to limit the downward movements of said inner slidable members.

4. In combination with a buffing bench having standards arranged upon the top of the same, vertical support members forwardly 10 of said standards and having inner slidable members provided with case-setting blocks designed to engage with the buff-wheels of said standards, pull-spring connections provided upon each side of said vertical support members and an integral hook projecting outwardly from the rear face of each

of the same, a movable support rod for each of said vertical support members and having their upper ends pivotally connected to said hooks and their lower ends provided 20 with an eyelet and movably mounted within a movable support secured to the floor, means to yieldingly support said vertical support members backwardly and forwardly, and means to shift the positions of the said 25 inner slidable members.

In testimony whereof I affix signature in presence of two witnesses.

MARTIN JELALLIAN.
